UNITED STATES PATENT OFFICE.

WESLEY E. WENNER, OF STONE CHURCH, PENNSYLVANIA.

BRAKE-BLOCK.

1,186,635.

Specification of Letters Patent. Patented June 13, 1916.

Application filed November 14, 1914. Serial No. 872,188.

To all whom it may concern:

Be it known that I, WESLEY E. WENNER, a citizen of the United States, residing at Stone Church, in the county of Northampton and State of Pennsylvania, have invented certain new and useful Improvements in Brake-Blocks, of which the following is a specification.

My invention relates to new and useful improvements in brake blocks.

The primary object of the invention is the construction of a block composed of two sections which are adjustably connected together.

With these and other objects in view the invention consists in the novel details of construction and arrangement of parts which will be more clearly understood from the following description and drawings, in which,

Figure 1 is a perspective view. Fig. 2 is a perspective view of the removable block. Fig. 3 is a top plan view of the stationary block, and Fig. 4 is a perspective detail of the spring for holding the sections together.

In carrying out my invention, the block is made in two sections which I will designate as the stationary block, as indicated at 1, and the removable block, as indicated at 2. It will be understood that the stationary block 1 may be secured to the brake beam in any suitable manner. As clearly shown in Fig. 1 of the drawings, the grain of wood runs in such a direction that it will be opposite to the movement of the wheel which it is adapted to engage. By this arrangement the block will wear a greater length of time and, if desired, may be treated with oil, creosote or other suitable preserving fluids.

The stationary block 1 is provided near one end in each side with openings 3 and near the opposite end on each side with a plurality of longitudinally spaced openings 4. A bolt 5 extends transversely of the stationary block for strengthening the same or for forming means whereby it may be secured to the brake beam. Each of the blocks are preferably concavo-convex, as clearly shown in the drawings, and in the concaved face of the stationary block are a plurality of openings 6, more clearly shown in Fig. 3 of the drawings. The stationary block is provided in one end with two

spaced openings 7 the purpose of which will be presently described.

The removable block 2 is provided on each side with a plurality of longitudinally spaced openings 8 and an L-shaped hook member 9 is adapted to be inserted in the openings. A pin 10 extends from the convexed face of the removable block, as more clearly shown in Fig. 2 of the drawings, and is adapted to enter one of the longitudinally spaced openings 6 in the concaved face of the stationary block. A groove or slot 11 is formed in the convexed face of the removable block 2 and extends from one end thereof, as clearly shown in Fig. 2 of the drawings. A wire hook member 12 is received in the groove or slot 11 and may be adjusted to extend to a greater or less degree beyond the end of the block. This hook member is held in its adjusted position by means of a screw 13, the head of which extends over the sides of the spring hook member. The ends of the hook member are adapted to be received in the openings 7 of the stationary block when the two blocks are secured together.

For securing the stationary and removable blocks together I have provided the member shown in detail in Fig. 4 of the drawings which consists of a cross bar 14 and two spring arm members 15 formed with the eyes 16 and right angle extensions 17. In assembling the blocks the cross bar 14 extends across the convexed face of the stationary block, near one end thereof, and the eye members 16 are adapted to engage the L-shaped hook members 9 on the sides of the removable block. The spring arm members are then bent, or brought under tension, until the right angle extensions enter one of the longitudinally spaced openings 4 in the sides of the stationary block near that end opposite to the end engaged by the cross bar 14. By this arrangement it will be seen that the two blocks are securely held together. It is often necessary to adjust the removable block whereby it will more securely engage the wheel and when this is desired the right angle extensions 17 are disengaged from the openings 4 and the eyes 16 disconnected from the hooks 9. The removable block 2 is then removed and the pin 10 may be engaged in any of the longi-

- tudinally spaced openings 6 formed in the concaved face of the stationary block 1. The hook members 9 are then removed and placed in the desired opening 8. It will be understood that the ends of the hook member 12 engage in the openings 7 in the stationary block and when the blocks are to be adjusted the screw 13 is loosened and the hook member adjusted into suitable position.
- 10 The screw is then again tightened to securely hold the hook members, and, as above stated, the ends enter the opening 7. When the several members have been adjusted and the blocks again assembled the securing member is again placed in position, the cross bar 14 engaging the convexed face of the stationary block, the eyes 16 engaging the hooks 9, and the right angle extensions 17 entering one of the longitudinally spaced openings 4. If desired, the spring holding member may be inverted or reversed whereby the right angle extensions will enter the perforations 3.

Having fully described the detailed construction of my device it is thought that the advantages will be readily understood. In the first place, the grain of the wood of the removable block runs crosswise whereby the greatest possible wear will be secured from the block. I have further provided a block in which a new face may be applied when one becomes worn. I have still further advantages by having the removable block adjustable in relation to the stationary block.

35 By providing the pin 10 adapted to enter one of the longitudinally spaced openings 6, I have provided against longitudinal movement of the blocks when together and the spring member securely holds the two blocks together. The hook member 12 entering the perforations 7 connect the two blocks at the end.

Having fully described the invention what I claim as new and desire to secure by Letters Patent is:—

1. A brake block comprising a stationary member, a removable member relatively adjustable in a longitudinal direction, and a yielding connection for securing said members together.

2. A brake block comprising a stationary member having a plurality of longitudinally spaced openings in one face thereof, a removable member having a pin extending from one face thereof and adapted to enter any one of the openings in the stationary member, and a yielding connection for securing said members together.

3. A brake block comprising a stationary member having a plurality of longitudinally spaced openings in one face thereof, a removable member having a pin extending from one face thereof and adapted to enter the openings in the stationary member, and spring arms connected to the removable

member and adapted to engage the stationary member.

4. A brake block comprising a stationary member, a removable member, and spring arms for securing the removable member to the stationary member.

5. A brake block comprising a stationary member having a plurality of longitudinally spaced openings in the sides thereof, a removable member, and spring arms connected to the removable member and adapted to enter the openings in the stationary member.

6. A brake block comprising a stationary member having a plurality of longitudinally spaced openings in the sides thereof, a removable member having hooks secured to the sides thereof, and spring arms connected to the hooks of the removable member and adapted to enter the perforations of the stationary member.

7. A brake block comprising a stationary member having a plurality of longitudinally spaced openings in the sides thereof, a removable block having a plurality of longitudinally spaced openings in the sides thereof, hook members adapted to enter the perforations of the removable member, and spring arms connected to the hooks and adapted to enter the perforations in the stationary member.

8. A brake block comprising a stationary member, a removable member, means for connecting the two members, said means comprising a cross bar engaging the face of the stationary member, and spring arms extending from the cross bar and adapted to engage the removable member.

9. A brake block comprising a stationary member, a removable member having hooks secured to the sides thereof, means for connecting the members, said means comprising a cross bar engaging the face of the stationary member, and spring arms extending from the cross bar, engaging the hooks of the removable member and the stationary member.

10. A brake block comprising a stationary member having a plurality of longitudinally spaced openings in the sides thereof, a removable member having hooks secured to the sides thereof, means for connecting the members, said means comprising a cross bar engaging the face of the stationary member, and spring arms extending from the cross bar, over the hook members and into the perforations of the stationary member.

11. A brake block comprising a stationary member having a plurality of longitudinally spaced openings in the sides thereof, a removable block having hooks secured to the sides thereof, spring arms having eyes formed intermediate the ends thereof and adapted to engage the hooks of the removable member, a cross bar connecting the

spring arms at one end and engaging the face of the stationary block, and right angle extensions formed on the opposite ends of the spring arms and adapted to enter the 5 openings in the stationary member.

12. A brake block comprising a stationary member having longitudinally spaced openings in the sides thereof, a removable member having longitudinally spaced openings 10 in the sides thereof, hooks adapted to enter the openings in the removable member, spring arms formed with eyes adapted to engage the hooks, a cross bar connecting the spring arms at one end and extending under the stationary block, and right angle extensions formed on the opposite ends of the 15 spring arms and adapted to enter the openings in the stationary block.

13. A brake block comprising a stationary 20 member having an opening in one end thereof, and a removable block having an adjustable hook extending from one end thereof and adapted to enter the opening in the stationary block.

14. A brake block comprising a stationary member having an opening in one end thereof, a removable member having a longitudinal recess in one end, and a hook seated in said recess adjustably connected to the 25 removable member and adapted to enter at its outer end the opening in the stationary member.

15. A brake block comprising a stationary member having spaced openings in one end 30 thereof, a removable member having a slot formed in one end thereof, and a hook adjustably connected in the slot and adapted to engage the openings in the stationary member.

16. A brake block comprising a stationary member having spaced openings in one end thereof, a removable block having a longitudinal slot formed in one face thereof and leading from one end, and a U-shaped hook 45 member adjustably connected in the slot and adapted to engage the openings in the stationary member.

17. A brake block comprising a stationary member having a plurality of longitudinally spaced openings formed in one face thereof 50 and longitudinally spaced openings in the sides, a removable member having longitudinally spaced openings formed in the sides thereof, a pin extending from one face of the removable member and adapted to enter the 55 longitudinally spaced openings in the face of the stationary member, hooks adapted to be secured in the longitudinally spaced openings of the removable member, spring arms having eyes formed intermediate the 60 ends thereof and adapted to engage the hooks of the removable member, a cross bar connecting the spring arms at one end and extending under the stationary block, and right angle extensions formed on the opposite 65 ends of the spring arms and adapted to enter the perforations in the sides of the stationary member.

18. A brake block comprising a stationary block having longitudinally spaced openings 70 formed in one face thereof, longitudinally spaced openings in the sides thereof, spaced openings in one end thereof, a removable member having longitudinally spaced openings formed in the sides thereof and a slot in 75 one face, a pin extending from one face of the removable member and adapted to enter the perforations in the face of the stationary member, a hook adjustably connected in the slot of the removable member, and adapted 80 to engage the openings in the end of the stationary member, hooks adapted to be secured in the openings formed in the sides of the removable member, and means engaging the hooks and adapted to engage the perforations in the sides of the stationary member 85 for connecting the blocks.

In testimony whereof I affix my signature in presence of two witnesses.

WESLEY E. WENNER.
